United States Patent Office.

JOHN J. NEWMAN, OF MIDDLETOWN, OHIO, ASSIGNOR TO ERWIN, WILSON AND COMPANY, OF SAME SLACE.

Letters Patent No. 67,567, dated August 6, 1867.

IMPROVED CLOTHES-DRIER.

The Schedule referred to in these Letters Patent and making part of the same.

TO ALL WHOM IT MAY CONCERN:

Be it known that I, J. J. NEWMAN, of Middletown, in the county of Butler, and State of Ohio, have invented a new and useful Improvement in Clothes-Horse Racks; and I do hereby declare the following to be a full, clear, and exact description of the same, reference being had to the accompanying drawings, forming part of this specification, and in which—

Figure 1 is a perspective view of my clothes-rack, the hinged arm extended.

Figure 2 is a view of the rack, the hinged arm and rack being closed.

Similar letters of reference indicate corresponding parts in the two figures.

This invention consists in attaching a hinged arm to a clothes-rack, which extends horizontally when in use, and when not in use may be dropped by the side of the rack so as to be out of the way.

In the drawings, A A A A represent the legs, B B B the rounds or slats, and C C the braces of my clothes-rack, the sides of the rack being united at the top by the hinges D D. Near the top of the rack, and attached to the leg A' by a pin, E, is an arm, F, hinged at f above the pin E. When the rack is used the hinged arm F is opened and rested upon the pin G in the side of the rack opposite to that holding the pin E. When not in use the arm F is closed upon its central hinge f and hangs from its supporting-pin E upon one side of the frame, as shown in fig. 2. There is a similar arm, F F, upon each side of the frame, and they are connected by slats or rounds to form a suitable support for the clothes while drying.

I do not claim the invention simply of an arm occupying the position on the rack which I have described this one as occupying, for such an arm is already in use; but what I do claim, and desire to secure by Letters Patent, is—

The combination of the hinge f, arm F, and pins E and G, when used in connection with a clothes-horse rack, substantially as and for the purpose set forth.

To the above specification of my improvement I have signed my hand this 12th day of April, 1867.

JOHN J. NEWMAN.
